UNITED STATES PATENT OFFICE.

FRENCH E. DENNISON, OF BELOIT, WISCONSIN, ASSIGNOR TO NATIONAL REFRIGERATION CORPORATION, OF BELOIT, WISCONSIN, A CORPORATION OF DELAWARE.

WATER-TEMPERATURE-CONTROL VALVE.

Application filed September 3, 1925. Serial No. 54,168.

This invention relates to devices for controlling temperature and while capable of many uses, is illustrated herein as associated with a water cooling unit.

5 Water coolers, such as are used in soda fountains, are subjected at different seasons of the year, to various loads. For instance, in the summer time a great deal more water is used than in the winter time and if the refrigerating apparatus by which the water is cooled is designed to meet the requirements of the warm weather peak loads too much refrigeration is produced in the winter time when little water is being used with the result, at such times, the water in the cooler becomes frozen and bursts the cooler.

It is highly desirable, therefore, in order to meet the varying demands upon the water cooler, that the tank in which the cooler is submerged be maintained at a temperature very close to the freezing point of water. When the demand for water is slight, the water will be drawn off at a temperature very close to 32° F. and when the demands 25 are heavy the low temperature in the tank surrounding the cooler will cool the water in the cooler very rapidly so that it will, when drawn off, be at a sufficiently low temperature.

30 It has heretofore been proposed to place in the cooling tank, a thermostatic element which, when a predetermined low temperature has been reached, would either shut off the refrigerating coils or admit water of a 35 higher temperature to the tank so as to prevent freezing of the water in the cooler. Such devices, however, have not proven satisfactory because they were depending entirely for their operation upon the variations in temperature of the water in the tank and the temperature of the whole volume of water in the tank would have to change considerably before the thermostatic element would operate. Furthermore, merely shutting off the refrigerating coils would not, in 40 many instances, prevent freezing of the water in the cooling coils and in the type where warmer water was admitted to the tank a great deal of water was wasted and the temperature of the water being cooled, would vary considerably instead of being maintained at a uniform and very low temperature as it is with the employment of my invention.

55 One of the primary purposes of my pres-

ent invention is to provide a temperature controlling device which will be extremely sensitive in operation and which will become operative only at freezing temperature. In other words, the device is not affected nor rendered operative by any temperature variations above 32° F., nor is it affected or rendered operative by temperatures below 32° F. It is affected, however, and rendered operative, not by temperature, but by the conversion of a medium from a liquid to a solid state and vice versa. By reason of this principle, the temperature of the liquid in the cooling tank may be maintained at all times with my device, at substantially 32° F. and the water in the cooler will be maintained very close to that temperature depending upon the amount that is being drawn off, but in no event, is the water in the cooler ever permitted to freeze so as to burst the cooler. The device, therefore, is controlled by latent heat rather than by temperature variations.

Another purpose of my invention is the provision of a device which will be affected to perform one operation by heat units transferred from the medium which surrounds it and will be affected to perform another operation by heat units delivered directly into the interior of the device. This principle renders my device not only extremely sensitive but highly efficient.

Other objects and many of the inherent advantages of my invention should be readily appreciated as the same becomes better understood by reference to the following description when considered in connection with the accompanying drawings. Referring to the drawings, Fig. 1 is a sectional view of a water cooler equipped with my invention. Fig. 2 is a longitudinal sectional view on a large scale of my novel control device and Fig. 3 illustrates the application of my invention to an electric circuit to make and break the same. Referring now to the drawing in detail, reference character 5 indicates generally a heat insulated cabinet or compartment of any preferred construction, such as is customarily used in soda fountains, the portion of the cabinet shown being adapted to form a chamber 6 which serves as a water cooler. This chamber is customarily filled with water to substantially the level indicated by reference character 7 so as to submerge the refrigerating coils 8 which are

connected with a refrigerating machine in the usual manner and the water cooling coils 9 of usual construction which receive their supply of water through a pipe 11 from the city mains and deliver it through a pipe 12 to the draw-off faucet 13.

It being desirable to maintain the water in the cooling elements 9 very close to the freezing point, the capacity of the refrigerating coils is such that the water in the chamber will be frozen adjacent to such coils and, usually depending on the amount of warm water that is entering the cooling elements 9 from the pipe 11, to a point in proximity to the cooling elements. The usual formation of ice is shown in Fig. 1 and indicated by reference character 14.

In order to prevent the water in the cooling elements 9 from freezing, my invention is so designed that when the ice formation approaches the cooling elements, water will be automatically drawn off and delivered from the elements thereby admitting to the elements water from the pipe 11 which is at a higher temperature so that freezing of the water in the cooling elements is prevented. With this end in view, pipe 15 leading from the lowermost element 9 is connected with the casing 16 of my improved device and a discharge pipe 17 leading from the casing, serves to deliver the water discharged from the cooling elements through the casing to the sewer or other desirable place of disposal. The freezing of the water within the elements is precluded by permitting this discharge of water at intervals sufficiently frequent to prevent the freezing.

From Fig. 2, it will be observed that the casing 16 is shaped to provide, in the conduit between the pipes 15 and 17, a valve seat 18 adapted to be closed by a valve 19 which is normally urged toward its seat by an expansion spring 21. The stem of the valve projecting through the valve passage surrounded by the seat is attached to a cylindrical member 22 adapted to reciprocate within the casing. The lower end of this cylindrical member is closed and intermediate its ends it is provided with a circumferential flange 23 to which the upper end of a corrugated expansible member 24, commonly called a bellows, is connected. The lower end of the bellows is attached to the circumferential flange of a base block 25 thereby forming a closed chamber within the bellows and around the cylindrical member 22. This chamber indicated by reference character 26 is filled with distilled water through a port which is later sealed by a plug 27. The filling of this chamber with water is done before the apparatus is all assembled and thereafter the filled bellows is introduced into a shell 28, the lower end of which may be closed by a bottom wall 29 and the upper end is then attached to the

lower end of the casing 16 by swaging in the upper edge of the shell as indicated at 31 or by threading it onto the casing. The assembly of the shell and casing provides another chamber outside of the bellows and this chamber is then filled with glycerine 32 or other suitable non-freezing solution having a low specific heat, through a port 33 which is then closed by a plug 34.

The conduit in the casing 16 through the valve seat 18 communicates with the space or chamber 35 within the lower end of the tubular member 22 through a plurality of ports 36 and a depending tube 37. Communication is established between the chamber 35 and the discharge pipe 17 through ports 38 and an annular passage 39.

The device being assembled as shown in Fig. 2 and the pipe 15 being connected with the lower element 9 of the water cooler so that the thermostatic device is exposed to the proximity of the cooler and the pipe 17 having been connected to any suitable point of discharge, the operation of the device is as follows: The expansible element 24 being normally contracted since the water in the space 26 does not expand or contract with variations in temperature to any appreciable extent, the valve 19 is normally closed against its seat and escape of water through the device from the element 9 of the cooler is prevented. The refrigerating apparatus being in operation, ice will begin to form around the refrigerating coils 8 and the formation will progress toward the cooler at 9. The glycerine or other fluid surrounding the expansible element 24 being nonfreezable and of low specific heat, the heat units of the distilled water in the chamber 26 will be conducted through this medium and the walls of the casing so that the temperature of this distilled water will be the same as that of the surrounding water in the compartment 6. The water of this compartment being city water and not entirely pure will freeze at a slightly lower temperature than the distilled water.

The frequent withdrawal of water from the cooling elements 9 through the faucet will tend to keep these elements at a slightly higher temperature than that of the water in the chamber 26. When the temperature of the distilled water within the device is reduced to 32° F. the same as the temperature of the water surrounding the casing, the maximum efficiency of the cooler will have been reached and this temperature will be maintained until approximately 142 heat units, that is the latent heat of water, have been abstracted from the distilled water in chamber 26, whereupon this water will begin to freeze at the periphery of the chamber between the corrugations of the expansible element 24 where it is coldest. The freezing and expansion of the distilled water within

these corrugated members will cause the expansible element 24 to expand longitudinally thereby lifting the valve 19 from its seat so as to permit an inflow of water through the 5 pipe 15 from the cooling element 9 and an outflow of water from this chamber 35 through the pipe 17. The water delivered through this course from the cooling elements is at least several degrees above freezing 10 and this relatively warm water delivered through the chamber 35 will warm the distilled water in the chamber 26 so as to melt the ice within the corrugations of the expansible element 24 and permit this element 15 to contract and close the valve 19. This delivery of water from the cooling elements permits warmer water from the pipe 11 to replace the water drawn off from the cooling elements thereby raising the temperature 20 within the cooling elements and preventing freezing.

By the use of my device the temperature of the water in the cooling coils may be maintained very close to the freezing point which, 25 of course, is the most desirable and efficient temperature and at the same time all danger of actually freezing the water in the cooling coils is entirely obviated.

In Fig. 3 I have illustrated the employment 30 of my invention to control an electric circuit. In this instance a rod or stem 35 extends upwardly from the valve 19 through a stuffing box 36 in the cap of the casing and is equipped at its upper end with an insulated abutment 37 adapted to close a switch indicated generally by reference character 38. This switch may be placed in an auxiliary 35 circuit to actuate a main switch 39 for stopping and starting a refrigerating machine, 40 for instance. Other uses of my invention will readily suggest themselves.

The construction, operation and many of the advantages of my invention should be understood from the foregoing without further description, and while I have shown and described a preferred form of the invention, obviously the structural details may be varied within wide limits without departing from the essence of the invention as defined in the following claims.

I claim:

1. A temperature control device comprising, a thermostatic element having a freezable actuating means operable in one direction upon the extraction from said element of heat units by the medium surrounding said element, and means controlled by said element for delivering heat units to the interior of the element for actuating the same in the other direction.

2. A temperature control device comprising, a thermostatic element including a freezable liquid normally subject to the temperature of a medium in which the device is immersed, and means rendered operable by the

solidification of said liquid to supply heat units to said element to reliquify said solidified liquid.

3. A temperature control device comprising, an expansible thermostatic element including a freezable liquid said element being adapted to be actuated only by the latent heat of said liquid said thermostatic element when actuated by latent heat serving to automatically admit heat units to the control device.

4. The combination, with a fluid conduit, of a valve interposed in said conduit, an expansible thermostatic element surrounding the conduit and adapted to be subjected to the temperature of a surrounding medium, and a connection between said element and said valve whereby the valve is opened to permit a liquid flow through said conduit upon the production of a predetermined condition in said element by the surrounding medium.

5. A temperature control device comprising, a casing provided with fluid inlet and outlet ports, a valve positioned between said ports to control the flow of fluid through the casing, a tubular member forming a portion of the conduit between said ports, and an expansible thermostatic element surrounding said member and connected with the valve through the intermediary of said member, said element being controlled by the temperature of a medium in which the element is submerged and by the temperature of the fluid in said tubular member.

6. In a temperature control device, the combination of a center hollow member, an expansible thermostatic element including a freezable liquid surrounding said member, and means controlled by said element for delivering fluid into said hollow member.

7. A temperature control device comprising, a casing provided with fluid inlet and outlet ports, a valve in said casing between the ports for controlling the flow of fluid therethrough, a hollow member connected with said valve and forming a portion of the fluid conduit between said ports, an expansible thermostatic element including a freezable liquid surrounding a portion of said tubular member and connected with said valve through the intermediary of said member, a shell surrounding the thermostatic element, and a liquid of low specific heat disposed within said shell around said thermostatic element.

8. In a temperature control device, the combination of a housing adapted to be submerged in a liquid to be controlled, a liquid of low specific heat disposed within said casing, an expansible thermostatic element including a freezable liquid submerged in said first mentioned liquid, a chamber within said thermostatic element, and means controlled by said element for admitting heat

- units to said chamber when said freezable solution causes said element to expand.
9. In a temperature control device, the combination of a hollow casing, provided within the inlet and outlet ports, a valve interposed between said ports and adapted to control the flow of a liquid therethrough, a tubular member depending from said valve and establishing communication between said ports when the valve is open, a thermostatic element including a freezable liquid surrounding said tubular member and subjected to the temperature of the fluid in said member, said thermostatic element being disposed within and spaced from the walls of said casing, and a non-freezing liquid of low specific heat surrounding said thermostatic element within the casing.
10. The combination, with a water cooling compartment containing cooling liquid refrigerating coils, and a submerged container for the water to be cooled, of a temperature control device connected with said water container and comprising a thermostatic device including a freezable liquid submerged in said cooling fluid, and a valve controlled by said element for permitting the delivery of water from said container upon the solidification of said freezable liquid, and means for directing the water so delivered into proximity to said thermostatic element to reliquify the previously solidified liquid.
11. The combination, with a water cooling compartment containing cooling liquid and refrigerating coils and a container for the water to be cooled submerged in said liquid, of a temperature control device connected with said container and including means for causing the delivery of a quantity of water from said container with its temperature closely approaching the freezing point.
12. The combination, with a cooling compartment containing a cooling fluid and refrigerating coils and a container for the water to be cooled submerged in said fluid, of a temperature control device connected with said container and including means actuated by latent heat only for causing the delivery of water from said container to prevent the actual freezing thereof within the container.
13. A temperature control device comprising an expansible thermostatic element containing distilled water substantially insensitive to temperature variations alone of the water, but adapted to be actuated by the latent heat of the water.
14. A temperature control device comprising an expansible thermostatic element containing a material substantially insensitive to temperature variations alone thereof surrounded by a non-freezing liquid of low specific heat, said thermostatic element being adapted to be actuated by the latent heat of said material.
15. A temperature control device comprising an expansible thermostatic element having the interior thereof filled with distilled water and the exterior thereof surrounded by glycerine, said element being insensitive to temperature variations alone of said water but adapted to be actuated by latent heat thereof.
16. A temperature control device for liquids comprising a compartment containing a non-freezing medium adapted to be placed in heat conducting relation to the liquid, the temperature of which is to be controlled, a second compartment containing a medium susceptible to a change in state but substantially insensitive to temperature variations alone of said medium and having a lag characteristic with respect to the medium in the first compartment, and means responsive to the temperature control device for automatically admitting heat units thereto.
17. A temperature control device comprising an expansible thermostatic element normally subject to the temperature of a cooling medium in which the device is immersed and adapted to be actuated only by the latent heat of the liquid included in said element for automatically delivering heat units to said element.
18. The combination with a cooling compartment containing a cooling fluid and a container for the water to be cooled submerged in said fluid, of a temperature control device associated with the container and submerged in the cooling fluid, said temperature control device automatically admitting heat units to the cooling container to prevent freezing thereof, without substantially affecting the condition of the body of cooling fluid in which the container is submerged.
19. In a device of the class described, a compartment containing a cooling fluid, a container submerged in said cooling fluid and containing water to be cooled therein, and means to supply heat units to the water within the container, said means being controlled by the temperature of the cooling fluid.
20. The combination with a water cooling compartment containing cooling liquid and refrigerating coils and a container for the water to be cooled submerged in said liquid, of a temperature control device connected with said container and including means for automatically causing heat units to be delivered to the container, and a delivery of a quantity of water from the container, when its temperature closely approaches the freezing point.
21. The combination with a water cooling compartment containing cooling liquid and refrigerating coils and a container for the water to be cooled submerged in said liquid, of a temperature control device connected with said container and including means for

automatically causing heat units to be delivered to the container, and a delivery of a quantity of water from the container, when its temperature closely approaches the freezing point, said heat units substantially unaffected by the condition of the cooling medium.

5

10

ing a thermostatic element including water adapted to actuate said element, said element being inoperable by temperature variations alone of said water but adapted to be actuated by the latent heat thereof.

In witness of the foregoing I affix my signature.

FRENCH E. DENNISON.

22. A temperature control device comprising
